UNITED STATES PATENT OFFICE.

JOHN M. WILLIAM LONG, OF HAMILTON, OHIO, ASSIGNOR TO THE LONG & ALLSTATTER COMPANY, OF SAME PLACE.

BALANCED CULTIVATOR.

SPECIFICATION forming part of Letters Patent No. 446,388, dated February 10, 1891.

Application filed September 10, 1890. Serial No. 364,587. (No model.)

To all whom it may concern:

Be it known that I, JOHN M. WILLIAM LONG, of Hamilton, Butler county, Ohio, have invented certain new and useful Improvements 5 in Balanced Cultivators, of which the following is a specification.

This invention pertains to that class of cultivators in which an arch structure supported by wheels drags two cultivator-beams, each 10 having capacity for a limited amount of independent fore-and-aft motion, and each beam being so coupled to the arch structure as to permit of the beams being independently swung sidewise or up or down, the driver 15 riding upon the vehicle.

My improvements relate to the system for balancing the supported load upon the wheel-axles, so as to relieve the neck-yoke of improper vertical strain.

20 My improvements will be readily understood from the following description, taken in connection with the accompanying drawings, in which—

Figure 1 is a side elevation of a cultivator 25 exemplifying my improvements, and Fig. 2 a perspective view of the arch portions at one side of the implement.

Parts not illustrated or specially referred to in the description are to be as usual.

30 Attention is directed to my patent, No. 329,919, particularly to the clevis set forth therein.

In the drawings, A indicates the tongue of the cultivator; B, the front arch-bar consisting of a cylindrical bar disposed at right angles to the tongue over the plow-couplings and rigidly secured at its center to the tongue; C, suspenders pivoted at their upper ends to this front arch-bar and provided at their 40 lower ends with bearings for the spindles of the plow-couplings, it being understood of course that Fig. 1 is a side elevation of an implement of double character, in which a cultivator-beam is disposed at each side of the tongue; D, the spindles of the plow-couplings journaled in the lower ends of the suspenders; E, the plow-beams coupled at their forward ends to the bases of the suspenders by means of the spindles D, which permit 45 the cultivators to be freely raised and lowered and by means of the usual vertical pivots

connecting the plow-beams with the coupling-spindles, so as to permit the cultivators to be swung to the right or left; F, the coupling-block united to the spindle and coupled to the plow-beam by the aforesaid vertical pivot; G, the clevis, like that in my earlier patent, connected to the coupling-block; H, the rear arch-bar disposed parallel with the front arch-bar and rigidly secured at its center to the tongue; J, standards provided at their upper ends with bearing journaled to the rear arch-bar and extending downwardly to the centers of the implement-wheels; K, stub-axles secured in the lower ends of the standards and projecting outwardly therefrom to receive the implement-wheels; L, the implement-wheels journaled on these stub-axles; M, the driver's seat supported on a prolongation of the tongue to the rear of the rear arch-bar; N, braces attached articulately at one end to the base of the standards J and at the other end to the front arch-bar, the latter attachment being adjustable to permit alteration of the length of the brace; O, blocks pivoted to the front arch-bar and mortised to receive the front end of the braces N, which slide through the blocks while being adjusted in length; P, a bolt passing through each block and its brace and serving to securely attach the brace to the block, the brace being provided with a series of holes for the bolt; Q, chain-eyes near the base of the standards and suspenders; R, chains connecting these eyes; S, chain-eyes in the suspenders above the couplings and in the plow-beams to the rear of the couplings; T, chains connecting these eyes; U, tie-bars engaging the rear arch-bar at the standards and the front arch-bar at the suspenders; V, the vertical pivots of the plow-couplings, and W the series of holes in the braces for the bolts P.

By an inspection of Fig. 1 it will be obvious that the tongue and the entire arch structure is supported by the implement-wheels; that the cultivators may be raised or lowered, swinging on the spindles D; that the cultivators may be swung to the right or left, swinging on the coupling-pivots V; that each cultivator may have an independent fore-and-aft motion as the horses pull unequally, this motion being permitted by the swinging of

the suspenders on the front arch-bar, and that this fore-and-aft motion of the cultivators will be limited by the chains R and T, which are sufficiently slack to permit only of the 5 desired fore-and-aft motion. It will also be understood that the weight of the tongue and the arch structure and the driver is borne by the stub-axles K and the implement-wheels, and that to this downward load thus supported is to be added the weight of the forward part of the beams plus whatever downward pressure the draft upon the clevis may produce. It is highly desirable that these 10 downward strains be met as fully as possible by the implement-wheels in order that the neck-yoke may be as free as possible from vertical strains. In other words, it is desirable that the load be accurately balanced upon the axles K, which means, again, that 15 the axles K shall be disposed under the center of gravity of the supported load; but the supported load and also the position of its center of gravity will alter with the weight of the driver and with the downward strain 20 upon the clevis. I therefore provide for a fore-and-aft shifting of the axles K. If the 25 axles are to be shifted to the rear, then braces

N are lengthened by removing bolts P and replacing them in holes farther toward the front end of the braces. If the axles are to be 30 shifted farther forward, then the braces are to be shortened. This fore-and-aft adjustment of the axles causes a swinging of the standards on the rear arch-bar.

The implement may be provided with the 35 usual sustaining-springs and with any of the usual accessories of this class of cultivators, and the usual provision is made for adjusting the width of the arch.

I claim as my invention—

In a cultivator, the combination, substantially as set forth, of a tongue, a pair of parallel arch-bars mounted thereon, suspenders articulated to the front arch-bar, cultivators with their beams articulated to the lower ends 40 of the suspenders, standards articulated to the rear arch-bar, implement-wheels journaled on axles at the bases of the standards, and braces adjustably connected to the front arch-bar and to the bases of the standards.

JOHN M. WILLIAM LONG.
